UNITED STATES PATENT OFFICE

FREDERICK A. RAMIG, OF BROOKLYN, NEW YORK

DESIGN FOR A HANDKERCHIEF OR SIMILAR ARTICLE

Application filed July 29, 1932. Serial No. 44,482. Term of patent 3½ years.

To all whom it may concern:

Be it known that I, FREDERICK A. RAMIG, a citizen of the United States, residing at No. 659 84th Street, in the borough of Brooklyn, city of New York, county of Kings, and State of New York, have invented a new, original, and ornamental Design for a Handkerchief or Similar Article, of which the following is a specification, reference being had to the accompanying drawing, forming part thereof.

The figure of the drawing is a plan view of the handkerchief showing my new design.

I claim:

The ornamental design for a handkerchief or similar article substantially as shown.

FREDERICK A. RAMIG,
